UNITED STATES PATENT OFFICE

101,761

DESIGN FOR A SPOON OR SIMILAR ARTICLE

Percy Bertram Ball, North Attleboro, Mass., assignor to The Watson Company, Attleboro, Mass.

Application September 10, 1936, Serial No. 64,798

Term of patent 7 years

To all whom it may concern:

Be it known that I, Percy Bertram Ball, a citizen of United States of America, residing at North Attleboro, in the county of Bristol and State of Massachusetts, have invented a new, original, and ornamental Design for a Spoon or Similar Article, of which the following is a specification, reference being had to the accompanying drawing, forming part thereof.

Figure 1 is a front or plan view; Figure 2, a cross-section at line 2—2 of Figure 1; Figure 3, a rear-view; and Figure 4, a side view of a spoon, showing my design.

I claim:

The ornamental design for a spoon or similar article as shown.

PERCY B. BALL.
